UNITED STATES PATENT OFFICE

JOHN SPOUSTA, OF RIVER ROUGE, MICHIGAN

FURNACE

Application filed February 11, 1927. Serial No. 167,409.

My invention relates to a new and useful improvement in a furnace adapted for use for heating purposes, and particularly a furnace for generating steam or one with which a hot water heating system may be used.

It is an object of the present invention to provide a furnace of this kind in which the maximum area of heating surface may be exposed to the heated gases, and the efficiency 10 of the furnace raised to a high degree.

It is another object of the present invention to provide a furnace of this kind formed from a plurality of sections which may be easily and quickly assembled.

15 Another object of the invention is the provision of a plurality of interlocking sections which, when assembled, provide baffled passages for the heated gases, thus retarding the gases in their passage from the combustion 20 chamber to the flue, and insuring a maximum combustion.

Another object of the invention is the provision of a furnace of this class which will be easily and quickly assembled, and economical of manufacture.

Other objects will appear hereinafter.

The invention consists in the combination and arrangement of parts hereinafter described and claimed.

25 The invention will be best understood by a reference to the accompanying drawings which form a part of this specification, and in which,

Fig. 1 is a front elevational view of the invention.

Fig. 2 is a sectional view taken on line 2-2 of Fig. 1, with a part broken away.

Fig. 3 is a sectional view taken on substantially line 3-3 of Fig. 2.

40 Fig. 4 is a sectional view taken on line 4-4 of Fig. 2.

Fig. 5 is a fragmentary sectional view taken on line 5-5 of Fig. 2.

45 As shown in the drawings, there is provided a base 9 projecting upwardly from which is a support 11 having formed in the forward side thereof the opening 10 which is closed by the door 12, a draught door 13 being provided in the door 12. The support 50 11 has, at its upper edge, an inwardly turned

flange 14, providing the opening 15 to afford communication between the ash pit positioned therebelow, and the combustion chamber positioned thereabove. Projecting upwardly from the flange 14 at the forward side thereof is a bead 16 adapted to engage in a groove 17 formed in the section which is positioned there above. This section, as shown in Fig. 2, comprises outer walls 18 and 19 which project upwardly from a base, the base resting 55 on the inturned flange 14. Positioned below the flange 14 and in alignment with the opening 15 is a grate 20. As shown in Fig. 2, an opening is provided in the lowermost section, this opening being closed by the door 21 which is mounted on the frame 22, this frame being secured to the section. An air vent 23 is formed in the door 21. Positioned inwardly of the inner wall 19 and formed integral with the inner wall 19 is a globe shaped member 24 60 which forms a chamber in communication with the space between the walls 18 and 19 through the necks 25. Projecting upwardly from the upper surface of the globe shaped member 24, centrally thereof, is a neck 26 65 which is interiorly threaded for the reception of a nipple 27. A superimposed section comprising an outer wall 28 is adapted for mounting on the lowermost section. A plurality 70 of these superimposed sections are used, each 75 section positioned above being constructed identical with the section positioned beneath, so that the section taken on line 5-5 illustrates the structure of a section identical with the section which is positioned on the lowermost section having the walls 19 and 18. In this sectional view, shown in Fig. 5, the outer wall 28 of the superimposed sections is bulged at 28' to provide a tubular extension projecting outwardly from the normal position of 80 the outer surface of the wall 28, and this tubular extension is provided with a base 29 having an opening formed therein registering with an opening formed in the top 30 of the lowermost section, these openings being interiorly threaded for the reception of a nipple 31 which serves to bind these sections together. As shown in Fig. 3 there are provided three of these tubular bulged formed 85 members, although the number may be va- 90 95 100

ried. The superimposed sections each have an inner wall 32 which is provided with the inwardly extending portion 33 intermediate its ends to provide a baffle forming structure and to provide the inwardly extending chamber 34 in which water may be contained.

In the drawing I have shown three of the superimposed sections, and the uppermost of these superimposed sections is bound by the nipple 51 to a dome 35, this dome having an outlet conduit 36 which connects to the outlet flue. The dome 35 is provided with a steam chamber 37 in communication with the interior of each of the superimposed sections. An outlet opening 38 is provided in the dome 35 in which a reducer 39 may be threaded to which the steam or water pipes, as the case may be, may be attached for conducting the heated water or the steam to desired locations.

Clean-out openings 40 are provided with plugs 41.

It will be noted that the inwardly extending portion 33 is in spaced relation to the top of the globe 24, thus providing between the inwardly projecting portion 33 and the top a passage 42 which is in communication with the combustion chamber 43 interiorly of the lowermost section. The superimposed sections already described may be termed herein outwardly positioned superimposed sections.

In the structure I have used a plurality of inwardly positioned superimposed sections, each of these sections comprising a tubular disc shaped body having the lower wall 44 and the upper wall 45. Projecting outwardly from the lower wall 44 is an interiorly threaded neck 46 of the same inside and outside diameter as the neck 26, so that when the neck 46 is positioned on the neck 26, these necks will be in registration, both as to their periphery and their inner surface. The neck 46 is interiorly threaded for the reception of the nipple 27, this nipple serving to bind the neck 46 in close engagement with the neck 26, and effect a water tight joint at this location, and establish communication between the interior of the disc shaped inwardly positioned section and the interior of the globe shaped member.

It is thus seen that the disc shaped member is in communication through its neck with the globe shaped member 24, with the space between the walls 18 and 19 and the lowermost section, and therefore also in communication with the interior of the superimposed outwardly positioned sections.

Projecting outwardly from the upper wall 45, centrally thereof, is a neck 47 which is interiorly threaded for the reception of a binding nipple 48, this binding nipple 48 being adapted for engaging in an interiorly threaded neck 49 of an adjacent superimposed inwardly positioned section. The number of these sections which are used is optional with the manufacturer, and the

nipples 48 serve to effect a water tight connection between the adjacent inwardly positioned sections and retain the same in communication with each other. The uppermost of the inwardly positioned sections is provided with a nipple 50 which extends through an opening 51 formed in the base 52 of the dome, so as to communicate the dome with each of these inwardly positioned sections. Projecting inwardly from the base 52 of the dome is a flange 53 to serve as a retainer for the packing 54 which is forced into engagement with the nipple 50 by the packing gland 55. The dome, as shown, is in communication through the nipple 31 with the outwardly positioned sections, this structure being apparent from Fig. 2.

It will be noted that the lower wall 44 of the inwardly positioned section is in spaced relation to the upper wall of the inwardly projecting portion 33 of the outwardly positioned section to provide a passage 56, this passage being in communication with the flue 36. Consequently, it is seen that the inwardly positioned sections co-operating with the inwardly directed portions 33 of the outer sections serve to form a baffled passage for the heated gases which are passing from the combustion chamber 43 to the flue 36, thus presenting to the heated gases a large heating surface, and at the same time retarding the passage of the gases to assure maximum heating of the system.

Inlet openings are provided in the lowermost section, each of these openings being closed by a suitable plug 57. These openings will serve as means for filling the interior of the inwardly positioned sections and the space between the outer and inner walls of the outwardly positioned sections with water for heating purposes. Suitable clean-out doors 58 are formed in the various sections.

It will be noted that the various sections may be easily and quickly assembled and that on account of having the inner sections separate and distinct from the outwardly positioned sections, the sections themselves are reduced in size so that a minimum amount of labour may be required for assembling. This formation also facilitates transportation of the furnace.

I have shown a pair of stay rods 59 projected through lugs 60 formed on the sections, these stay rods being used, when desired, to further bind the outwardly positioned sections together.

While I have illustrated and described the preferred form of construction, I do not wish to limit myself to the precise form of structure shown, but desire to avail myself of such variations and modifications as may come within the scope of the appended claim.

Having thus described my invention what

I claim as new and desire to secure by Letters Patent is:

A furnace of the class described comprising a plurality of duplicate double walled sections, with the spaces between said walls in intercommunication, the inner wall of each of said sections being bulged inwardly away from the outer wall, a plurality of centrally disposed, disk-like hollow intercommunicating sections enclosed by said double walled sections, the edges of adjacent disk like sections extending in overlapping, spaced relation to said bulged walls, the space between said bulged walls and disk-like sections forming sinuous passages for the escape of gas, a supporting section comprising spaced walls forming continuations of the walls of the double walled sections, the space between said walls being in communication with the space between said double walled sections, a centrally disposed hollow globe-shaped member connected to said supporting section and disk-like members, and establishing communication between the enclosed spaces of said sections and members, and providing support for said disk-like members, a hollow top section communicating with said double walled sections and said disk-like sections and having an exit flue in communication with said sinuous passages, said supporting section inclosing a combustion chamber space.

In testimony whereof I have signed the foregoing.
